(57) **CLAIM**

The ornamental design for a bag holder, as shown and described.

DESCRIPTION

FIG. 1 is a front perspective view of a bag holder showing the first embodiment of my new design;

FIG. 2 is a right side elevation view thereof;

FIG. 3 is a bottom plan view thereof;

FIG. 4 is a top plan view thereof;

FIG. 5 is a rear perspective view thereof;

FIG. 6 is a detailed enlarged view thereof, taken from FIG. 5;

FIG. 7 is a right side view thereof, with the peg removed;

FIG. 8 is a right side view thereof, in an alternate position;

FIG. 9 is a rear perspective view of a bag holder showing a second embodiment;

FIG. 10 is a detailed enlarged view thereof, taken from FIG. 9;

FIG. 11 is a right side elevation view thereof; and,

FIG. 12 is a right side view thereof, in an alternate position.
